SELF-PULSING OSCILLATOR

Harold W. Lord, Schenectady, N. Y., assignor to
General Electric Company, a corporation of
New York

Application April 27, 1945, Serial No. 590,564

9 Claims. (Cl. 250—36)

1

My invention relates to pulse generating circuits and, more particularly, to self-pulsing oscillator circuits of the type employed in connection with pulse transmitters and the like.

It is a general object of my invention to provide a new and improved self-pulsing oscillator which at once employs a minimum of equipment and is capable of producing pulses of considerable power.

It is a further object of my invention to provide, in a self-pulsing oscillator circuit, a non-oscillatory pulse generating circuit of the multivibrator type in which one of the multivibrator tubes is used also as the oscillator tube.

It is a still further object of my invention to provide new and improved non-oscillatory means for definitely determining the conductive interval of a self-pulsing oscillator.

It is another object of my invention to provide a self-pulsing oscillator in which all discharge devices are normally cut off so that the duty cycle upon all devices is very low.

In accordance with my invention, a triggered pulse generating circuit of the normally non-conductive multivibrator type shown in my copending application, Serial No. 587,689, filed April 11, 1945, is connected so that the triggered discharge device produces high frequency oscillations during the pulse intervals. In this type of multivibrator circuit, the triggered pulser tube is regeneratively connected so that output pulses are abruptly built up and abruptly terminated, thereby to render the output pulses substantially rectangular in shape. The other discharge device conducts only momentarily in delayed response to initiation of conduction in the pulser tube and by its conduction impresses upon the pulser tube a shut-off impulse of short duration. The duty cycle on both tubes is thus very low. In the self-pulsing oscillator arrangement of the subject application, the pulser tube is regeneratively coupled for high frequency oscillations independently of the non-oscillatory pulse generating circuit.

The features of my invention which I believe to be novel are set forth with particularity in the appended claims. The invention itself, both as to its organization and manner of operation, together with further objects and advantages thereof, may best be appreciated by referring now to the following detailed specification taken in conjunction with the accompanying drawing the single figure of which is a schematic circuit diagram of a self-pulsing oscillator embodying my invention.

The oscillator circuit illustrated in the drawing

2

comprises an electron discharge device 1 having an anode 2, a cathode 3, and a control electrode 4. In order to produce oscillations of predetermined frequency, there is employed a tuned oscillatory feedback circuit of any desired type. In the drawing, I have shown a modified Hartley oscillator circuit comprising a pair of inductors 5 and 6 connected in series circuit relation by a pair of blocking capacitors 7 and 8. The capacitors 7 and 8 prevent oscillator frequency currents from flowing through the non-oscillatory pulse generating circuit to be described hereinafter. The inductors 5, 6 and the capacitors 7, 8 are shunted by a tuning capacitor 9. The resonant circuit thus formed is connected at one side to the anode 2 of the discharge device 1 and at the other side to the control electrode 4. The mid-point between the capacitors 7, 8 is connected to ground, and the cathode 3 of the discharge device 1 is grounded through a cathode resistor 10. Anode potential positive with respect to ground is supplied to the oscillator tube 1 from a suitable source of unidirectional current supply B+ through an anode resistor 11. It will be understood by those skilled in the art that the circuit above described oscillates in a well-known manner, the coupling between the anode-to-cathode and control electrode-to-cathode circuits being sufficient to provide the necessary regenerative feedback.

10 The pulse generating circuit for alternately rendering the oscillator tube 1 conductive and non-conductive at predetermined intervals comprises the discharge device 1, a transformer 12, and a second discharge device 13. The discharge device 13 includes an anode 14, a cathode 15, and a control electrode 16, and is utilized only to provide cut-off impulses for the oscillator tube 1. The cathode 15 is grounded and anode potential is supplied to the anode 14 from the positive potential source B+ through an anode resistor 19.

15 The pulse transformer 12 has three windings 20, 21, and 22, the windings 20 and 21 being connected to provide regenerative feedback between the anode 2 and control electrode 4 of the oscillator device 1 independently of the tuned oscillator feedback circuit, and the winding 22 providing delayed positive impulses to initiate conduction in the shut-off tube 13. The transformer winding 21 is connected at one end to ground, and at the other end to the anode 2 of the discharge device 1 through a coupling capacitor 23 and the inductor 5. The capacitor 7 by-passes the ungrounded end of the winding 21 to ground for high frequency currents. The ungrounded end of the transformer winding 21 is also connected to the control

electrode 16 of the discharge device 13 through a timing capacitor 24, and to the positive potential source B+ through a current limiting resistor 25 for polarization of the core. One end of the transformer winding 20 is connected through a resistor 17 to a suitable source of unidirectional potential negative with respect to ground and indicated upon the drawing at C-. The other end of the winding 20 is connected through the inductor 6 to the control electrode 4 of the discharge device 1. The capacitor 8 by-passes this grid connection to ground potential for high frequencies. A damping resistor 26 is connected across the terminals of the transformer winding 20. The source C- is by-passed to ground for high frequencies through a capacitor 18. The transformer winding 22 is similarly connected at one end to the potential source C- and at the other end through a resistor 27 to the control electrode 16 of the discharge device 13. The winding 22 is by-passed for high frequency currents by a capacitor 22a. The transformer windings 20, 21, and 22 are so arranged upon the core that adjacent ends of the windings, as shown on the drawing, are of like polarity.

Triggering potential is supplied to the pulse generating circuit from a suitable source 29 of negative triggering impulses through a capacitor 30 to the ungrounded terminal of the transformer winding 21. Shut-off impulses are fed back from the discharge device 13 to the oscillator tube 1 through a coupling capacitor 28 between the anode 14 of the device 13 and the control electrode 4 of the tube 1.

I wish to have it understood that, while I have shown by way of illustration a modified Hartley circuit connected to control high frequency oscillations in the discharge device 1, my invention is not necessarily limited to such an oscillator circuit, but that if desired any preferred type of oscillator coupling may be used between the anode and control electrode of the discharge device 1. For example, if desired, a resonant cavity type of oscillator may be employed.

In operation, negative triggering impulses are supplied from the source 29 of trigger potential to the ungrounded end of the transformer winding 21. The triggering impulses initiate, at this end of the transformer winding, recurrent negative voltage pulses. Each negative voltage pulse on the transformer winding 21 induces in the transformer winding 20 a positive grid pulse. The induced grid pulse in the winding 20 overcomes the negative bias of the control electrode 4 derived from the source C-, thereby to render the discharge device 1 conductive and to initiate oscillations therein under the control of the oscillator tuning circuit 5, 6, 9. As soon as the discharge device 1 becomes conductive, the anode potential decreases, thereby to drive the ungrounded end of the transformer winding 21 further negative by coupling through the capacitor 23, so that the control electrode 4 is driven further positive by regeneration through the transformer windings 20 and 21. In this manner, the discharge device 1 is driven rapidly to a condition of maximum conduction, so that the pulse of oscillations across the anode resistor 11 has a very sharp leading edge. Thus, regeneration through the transformer 12 maintains the discharge device 1 in a state of oscillation for a predetermined period which may be longer than the duration of the triggering impulses from the source 29. The maximum conduction condition in the oscillator tube 1 is preferably not at current

saturation, but rather the transformer 12 is so adjusted and damped that, in combination with the tuned grid circuit 5, 6, 9, it permits the grid voltage to stabilize at an optimum bias value for oscillation. Indeed, the resistor 17 in the grid pulsing circuit of the device 1 may so load the grid 4 that the bias potential maintained on the grid is negative throughout the oscillatory interval.

To ensure definite termination of the pulse of oscillations across the anode resistor 11 at a desired time, the discharge device 13 is employed to provide shut-off impulses. The discharge device 13 is normally non-conductive by reason of the negative bias derived from the source C- through the transformer winding 22 and the resistor 27. As soon as conduction is initiated in the discharge device 1, the negative potential maintained at the ungrounded end of the transformer winding 21 by pulse conduction through the discharge device 1 drives the control electrode 16 of the discharge device 13 more than normally negative by reason of the coupling through the capacitor 24, thereby to maintain the discharge device 13 non-conductive without increasing the charge upon the capacitor 24. The negative pulse across the winding 21, however, induces in the winding 22 a similar pulse of such polarity that it tends to reverse the charge upon the timing capacitor 24 thereby to drive the control electrode 16 of the discharge device 13 positive. Reversal of the charge upon the capacitor 24 in response to the induced pulse across the transformer winding 22 is delayed exponentially by the characteristics of the RC circuit including the capacitor 24 and the resistor 27. After a predetermined time delay, however, the positive pulse across the transformer winding 22 overcomes the negative potential maintained upon the control electrode 16 from the negative source C- and by coupling through the capacitor 24, so that the discharge device 13 is rendered conductive. As soon as the discharge device 13 conducts, the potential of its anode 14 decreases abruptly, and the negative pulse thus formed is coupled through the capacitor 28 to the control electrode 4 of the oscillatory discharge device 1. The capacitors 18 and 28 and the resistor 17 provide an alternating current output circuit for the device 13. When the control electrode 4 is driven negative by conduction in the discharge device 13, conduction in the discharge device 1 is abruptly terminated. As soon as the anode current of the discharge device 1 begins to decrease, regeneration through the transformer windings 20 and 21 aids in the abrupt termination of conduction in the discharge device 1. Additional regeneration is provided through the discharge device 13, for as soon as the potential of the anode 2 increases the grid 16 is driven more positive by coupling through the capacitor 24. This increases conduction in the discharge device 13 and thus increases the negative potential impressed upon the grid 4 by coupling through the capacitor 28.

As soon as the oscillator tube 1 cuts off, the negative voltage pulse across the transformer winding 21 is terminated, thereby to terminate the positive voltage pulse across the transformer winding 22 so that the negative bias source C- is effective to again reverse the charge upon the capacitor 24 and thus to cut off the discharge device 13. Both discharge devices 1 and 13 remain non-conductive until such time as another triggering impulse appears at the coupling capacitor 30.

It will now be evident that the pulse duration of the oscillations appearing across the anode resistor 11 is determined solely by the characteristics of the RC circuit 24, 27 so that, by change in the capacity of the capacitor 24, the duration of the pulsed oscillations may be controlled. Moreover, regeneration through the transformer windings 20 and 21 is effective both upon initiation and termination of the oscillations of the discharge device 1, so that substantially rectangular pulses of oscillations are formed. It will also be evident that, by providing a pulse generator of the multivibrator type in which both discharge devices are normally non-conductive, the oscillator tube being combined with one of the multivibrator tubes and the other tube being conductive only instantaneously to provide shut-off impulses, a minimum of equipment, in addition to the oscillator tube itself, is required.

It will be evident to those skilled in the art that the accuracy of timing may be increased, if desired, by substituting for the timing capacitor 24 an open ended artificial transmission line section, as described in my foregoing copending application.

While I have described only a preferred embodiment of my invention by way of illustration, many modifications will occur to those skilled in the art, and I, therefore, wish to have it understood that I intend in the appended claims to cover all such modifications as fall within the true spirit and scope of my invention.

What I claim as new and desire to secure by Letters Patent of the United States is:

1. In combination, a direct current source, an oscillator energized from said source and comprising a first electron discharge device having an anode, a cathode and a control electrode, an anode-cathode circuit for said discharge device, oscillator coupling means for deriving from said anode-cathode circuit and supplying to said control electrode oscillatory energy in proper phase to support oscillations in said circuit, a second electron discharge device, means normally maintaining both said discharge devices non-conductive, means for recurrently rendering said first discharge device conductive thereby to initiate oscillations therein, time element means responsive to initiation of conduction in said first discharge device for rendering said second discharge device conductive, and means substantially instantaneously responsive to conduction in said second discharge device for rendering said first discharge device non-conductive thereby to terminate oscillations therein.

2. In combination, a direct current source, an oscillator energized from said source and comprising a first electron discharge device having an anode, a cathode and a control electrode, an anode-cathode circuit for said discharge device, oscillator coupling means for deriving from said anode-cathode circuit and supplying to said control electrode oscillatory energy in proper phase to support oscillations in said circuit, a second electron discharge device, means for normally maintaining both said discharge devices non-conductive, triggering means for rendering said first discharge device conductive to initiate oscillations therein, time element means responsive to initiation of conduction in said first discharge device for rendering said second discharge device conductive, and means responsive to conduction in said second discharge device for causing both said devices to return rapidly to non-conductive condition.

3. In combination, a direct current source, an oscillator energized from said source and comprising a first electron discharge device having an anode, a cathode and a control electrode, an anode-cathode circuit for said discharge device, oscillator coupling means for deriving from said anode-cathode circuit and supplying to said control electrode oscillatory energy in proper phase to support oscillations in said circuit, a second electron discharge device, biasing means for normally maintaining both said discharge devices non-conductive, a source of triggering potential impulses arranged recurrently to overcome the bias of said first discharge device thereby to render said first discharge device conductive and initiate oscillations therein, regenerative means independent of said oscillator coupling means for maintaining said first discharge device conductive independently of said triggering source, time element means energized by said regenerative means for rendering said second discharge device conductive a predetermined time after initiation of oscillations in said first discharge device, and means substantially instantaneously responsive to conduction in said second discharge device for terminating said oscillations.

4. In combination, a direct current source, an oscillator energized from said source and comprising a first electron discharge device having an anode, a cathode and a control electrode, an anode-cathode circuit for said discharge device, oscillator coupling means for deriving from said anode-cathode circuit and supplying to said control electrode oscillatory energy in proper phase to support oscillations in said circuit, a second electron discharge device having an anode, a cathode and a control electrode, biasing means normally maintaining both said discharge devices non-conductive, a source of triggering potential impulses connected to render said first discharge device conductive, regenerative coupling means independent of said oscillator coupling means and including a transformer connected between the anode and control electrode of said first discharge device, time element means energized from said transformer and arranged to overcome the bias of said second discharge device a predetermined time after each initiation of conduction in said first discharge device, and coupling means substantially instantaneously responsive to conduction in said second discharge device for rendering said first discharge device non-conductive.

5. A self-pulsing oscillator comprising a pair of electron discharge devices having anodes, cathodes and control electrodes, a source of negative biasing potential arranged normally to maintain both said discharge devices non-conductive, an oscillatory tuned circuit regeneratively coupling the anode and control electrode of one of said discharge devices to support oscillations therein, a three-winding transformer having one winding coupled to each of said control electrodes and a third winding coupled to the anode of said first discharge device, said transformer providing non-oscillatory regenerative coupling independent of said oscillator coupling between the anode and control electrode of said first discharge device, a source of negative triggering impulses coupled to the anode of said first discharge device to render said device conductive and thereby to initiate oscillations, means comprising a timing capacitor and discharge resistor for energizing the control electrode of said second discharge device from said transformer so as to overcome the bias of said second discharge

device gradually in response to initiation of conduction in said first discharge device, and means substantially instantaneously responsive to conduction in said second discharge device for terminating said oscillations.

6. A self-pulsing oscillator comprising a pair of electron discharge devices, means normally maintaining both said discharge devices non-conductive, oscillator coupling means connected to one of said discharge devices for supporting oscillations therein, triggering means for supplying a potential impulse to said one discharge device to render it conductive and to initiate oscillations therein, time element means responsive to initiation of said conduction in said first discharge device for rendering the second of said discharge devices conductive after a predetermined interval, means responsive to conduction of said second device for returning said first device to non-conductive condition, and means responsive to termination of conduction in said first device for rendering said second discharge device non-conductive.

7. A self-pulsing oscillator comprising a pair of electron discharge devices having input and output circuits, a tuned circuit regeneratively coupling the input and output circuits of one of said discharge devices to support oscillations therein, separate non-oscillatory means regeneratively coupling the input and output circuits of said one discharge device, means for normally maintaining both said devices non-conductive, a source of triggering impulses arranged recurrently to render said one discharge device conductive thereby to initiate oscillations therein, time element means including said non-oscillatory coupling means and the second discharge device for terminating said oscillations a predetermined time after their initiation, and means responsive to termination of conduction in said one discharge device for rendering said second discharge device non-conductive.

8. A self-pulsing oscillator comprising a pair of electron discharge devices having input and output circuits, a tuned circuit regeneratively coupling the input and output circuits of one of said discharge devices to support oscillations therein, separate non-oscillatory means regeneratively

coupling the input and output circuits of said one discharge device, means for normally maintaining both said discharge devices non-conductive, a source of triggering impulses arranged recurrently to render said one discharge device conductive thereby to initiate oscillations therein, time element means energized by said non-oscillatory coupling means and arranged gradually to overcome the bias of the second discharge device thereby to render said second discharge device conductive a predetermined time after initiation of oscillations in said first discharge device, and means instantaneously responsive to conduction in said second discharge device for terminating said oscillations.

9. In combination, a pair of electron discharge devices having input and output circuits, biasing means arranged normally to maintain both said discharge devices non-conductive, oscillatory coupling means for deriving from the output circuit and supplying to the input circuit of one of said discharge devices oscillatory energy in proper phase to support oscillations therein, second coupling means rendering said discharge devices alternatively conductive, a source of triggering impulses connected recurrently to render said one discharge device conductive, time delay means responsive to initiation of conduction in said one discharge device for momentarily disabling said second coupling means after a predetermined time thereby to render the other of said discharge devices conductive, and means responsive to termination of conduction in said one discharge device for rendering said other discharge device non-conductive.
